UNITED STATES PATENT OFFICE

2,482,910

MOUNTING FOR SOIL TREATING UNITS

Henry C. Hettelsater, Whitefish Bay, Wis., assignor to Harnischfeger Corporation, Milwaukee, Wis., a corporation of Wisconsin

Original application December 13, 1943, Serial No. 514,177. Divided and this application December 8, 1944, Serial No. 567,228

6 Claims. (Cl. 94—40)

1

This invention relates to apparatus for removing native soil material and intermixing it with a bonding agent and returning it to a location near to the one from which it was removed on the surface of the earth for the purpose of creating a strengthened or paved layer suitable for resisting weathering action and sustaining traffic, and it resides in an improved form of such apparatus wherein the instrumentalities by which the native soil is removed are subject to precise control, thus permitting a substantially uniform layer of soil to be removed while the apparatus is passing over changes of contour of the earth and in which such removal is carried forward continuously by progressive removal of small increments so as to deliver the removed material in substantially pulverized condition accessible to a bonding agent to be introduced and in which the removed and pre-pulverized material is additionally pulverized by an impact action against a moving target capable of returning insufficiently pulverized material for successive impacts, and in which pulverized material is impelled in a regulated and positive manner into milling apparatus in which added bonding agent may be thoroughly intermixed with the soil undergoing treatment prior to its return to its intended position on the surface of the earth.

Substantial advantages may be obtained in the construction of low cost pavements under many conditions by employing the native soil already in place over the course which the pavement is intended to follow and by mixing such soil thoroughly with a bonding agent such as Portland cement or bituminous material. In order to accomplish this, the soil material must be removed, pulverized thoroughly, mixed with the bonding material, returned to the position on the roadway desired and then rolled to compact it. Numerous appliances or series of appliances for accomplishing these operations have been proposed from time to time and many have been constructed and used. Such apparatus, however, has been subject to serious drawbacks, either because of its complexity and cost or because of its inability to follow the varying contour of the grade being worked upon without difficult and expensive improvisations or because of inadequate pulverization of the excavated material, or because of defective mixing of the bonding agent with the material before returning the same to the roadway, or for other reasons. It is one object of this invention to obviate the difficulties heretofore experienced and to provide an apparatus capable of being so controlled as to op-

2

erate successfully and easily where changes in grade are involved and which will produce a degree of pulverization and uniformity of admixture of bonding agent which will result in a pavement of superior strength and endurance.

5 This invention is herein described by reference to the accompanying drawings forming a part hereof in which there is set forth by way of illustration and not of limitation one specific form in which the apparatus of this invention may be embodied.

10 This application is a division of my copending application Serial No. 514,177, filed December 13, 1943, which has matured as Patent No. 2,424,459, and relates more particularly to the supporting and drive of the soil treating unit.

15 In the drawings:

Fig. 1 is a side elevation view of one form of the apparatus of this invention;

20 Fig. 2 is a sectional view in elevation for the purpose of showing certain details of the adjusting apparatus viewed through the plane 2—2, indicated in Fig. 1;

25 Fig. 3 is a top plan view of the apparatus shown in Fig. 1;

Fig. 4 is a diagrammatic showing of the drive system employed in the apparatus shown in Fig. 1;

30 Fig. 5 is an enlarged detailed top plan view with parts broken away and in section of the treating part of the apparatus of this invention;

Fig. 6 is a diagrammatic showing of the piping connections employed in the control system of the apparatus.

35 The form of the apparatus of this invention shown in the drawings, particular reference being made to Figs. 1 and 3, comprises as principal elements a transporting unit 1 and a soil treating unit 2.

Transporting unit

40 *Chassis.*—The chassis of the transporting unit 1 is made up of a pair of endless track type treads 3 mounted one on each side of the machine to form a tractor base, the same being of conventional construction and therefore generally depicted in outline only. The tractor base is secured to and supports a main frame made up of two transversely joined longitudinally extending box girders 4 and 5 which serve additionally as 45 fluid supply tanks in a manner and for purposes described more in detail hereinafter. A transverse member 6 at the rear of the machine joins the tanks 4 and 5 while a transverse member 7 joins the tanks 4 and 5 at the forward end of the machine to complete the main frame. Between

the tanks 4 and 5 and carried upon the cross members 6 and 7 are a pair of longitudinal sub-frame members 8 and 9.

Propelling drive system.—Mounted on the forward end of the sub-frame members 8 and 9 is an engine 10 having an automotive type engine clutch facing rearwardly in the housing 11 from which emerges a stub shaft 12 operatively connected to the driven part of the clutch. The shaft 12 carries a sprocket wheel 13 contained within a guard 14 and engaged by a chain 15 to be described in greater detail hereinafter. The rear end of shaft 12 terminates at and is drivingly connected to the driving part of a torque limiting friction clutch 16. The clutch 16 serves a protective function made advisably by the fact that the capacity of engine 10 is such as to be substantially in excess of that required for simple propulsion of the apparatus and accidental stalling of the propelling mechanism might otherwise result in damage to parts properly proportioned for the duty expected of them but not proportioned for the excessive capacity of the engine 10. The clutch 16 is therefore arranged to slip whenever a condition arises which would tend to apply thereto a torque in excess of that entailed under the most severe propelling conditions to be expected.

The clutch 16 is drivingly joined by a connecting shaft 17 with a change speed gear transmission 18 of conventional automotive type having four selective forward speeds and one reverse speed. A shifting lever 19 extends upwardly from the transmission 18 within reach of a person operating the apparatus, standing on a platform 20 or seated on a seat 21. Directly coupled to the output end of the transmission 18 is a selective reverse and reduction gear transmission 22 having one selective forward speed and one selective reverse speed. The output of reverse and reduction gear transmission 22 is in turn coupled directly with a worm driven differential gear 23, having two laterally extending propelling shafts, one on each side, carrying steering brakes 24 and 25 and propelling sprockets 26 and 27 contained respectively within the guards 28 and 29.

Referring now particularly to Fig. 1, the sprocket 27 is shown in meshing engagement with an endless chain 30 which passes over an idler take-up sprocket 31 and around and in meshing engagement with a tractor drive sprocket 32 all shown in dotted lines, the latter being in driving engagement with the tread 3 appearing. In like manner, but not shown, the sprocket 26 is joined in driving engagement with the tread 3 on the opposite side of the machine.

Propelling control system.—Actuator linkages for the steering brakes 24 and 25, of conventional type and therefore not shown to avoid confusion in the drawings, are joined to a steering lever 32 (see Fig. 3) in such manner that when the lever 32 is thrust forwardly brake 24 is applied and when pulled rearwardly brake 25 is applied. In mid position of the lever 32, neither brake is applied and the lever 32 is advantageously arranged to be self returning to said mid position. In this way when the apparatus is being propelled, steering may be accomplished through the cooperative action between the brakes 24 or 25 on the one hand and the differential gear 23 on the other hand. For example if brake 24 be applied the rate of driving of the tread on the left side of the machine is retarded and that on the right side of the machine accelerated an equivalent amount and the apparatus turns toward the left.

If brake 25 is applied, the opposite result is obtained, and if neither brake is applied, the apparatus travels in a straight line unless and until some external agency interferes.

5 The rate at which the apparatus is moved, its direction, and the amount of tractive effort which it is capable of exerting is regulated by means of the selective transmissions 18 and 22. To control these instrumentalities the shifter member 19 previously referred to is employed to control transmission 18, and the shifter member of transmission 22 is extended by conventional means not shown and omitted to avoid confusion in the drawings, to a shifting lever 33 mounted within reach of the operator. To permit shifting of the transmissions 18 and 22, the clutch previously referred to and contained within the housing 11, is connected by conventional means not shown, and omitted from the drawing to avoid confusion, to a clutch shifting lever 34 mounted within reach of the operator.

By means of the selective change speed gearing arrangement shown and described, the operator has at his disposal, with the transmission 22 in forward driving position, four forward driving speeds and one reverse speed depending upon the position of transmission 18 which is selected. With the transmission 22 in reverse position the operator has at his disposal an additional forward driving speed and four reverse speeds. I prefer to employ in the case of the transmission 22 a very substantial reduction, say about four and one-half to one, in the driving ratio of the forward speed and a driving ratio near to unity for the reverse driving speed. In the case of transmission 18, prefer that the driving ratios of the various speeds be approximately one to one for the highest forward speed, about two to one for the higher intermediate forward speed, and about three to one for the lower intermediate forward speed, about six and one-half to one for the lowest forward speed and about eight to one for the reverse speed. Compounding the ratios of the two transmissions, the over-all reduction for the several selective combinations result in the following:

Forward Speeds		Ratio
Transmission 18	Transmission 22	
Low.....	Forward.....	About 29 to 1
Lower intermediate.....	do.....	About 13 to 1
Higher intermediate.....	do.....	About 9 to 1
High.....	do.....	About 4½ to 1
55 Reverse.....	Reverse.....	About 8 to 1

Reverse Speeds		Ratio
Transmission 18	Transmission 22	
Reverse.....	Forward.....	About 36 to 1
Low.....	Reverse.....	About 6½ to 1
Lower intermediate.....	do.....	About 3 to 1
Higher intermediate.....	do.....	About 2 to 1
65 High.....	do.....	About 1 to 1

From this it will be observed that very low forward working speeds are provided but in reverse a much greater rate of travel is available. Taking advantage of this relationship I prefer to employ such a reduction in the driving ratio of the worm in differential 23 and in the propelling sprockets that forward working speeds as low as about 5 feet per minute are available in which event speeds as high as about 2 miles per hour

may be attained in reverse, so that the machine may transport itself for short distances to and from or between jobs or for return travel to take up an adjacent parallel pass without an undue expenditure of time.

The engine 10 may be regulated as to speed by means of a throttle with or without a governor as desired and these parts being of conventional form are not shown.

Soil treating unit

Mounting.—The soil treating unit 2 as appears in Fig. 1 is mounted upon the downwardly and rearwardly extending arms 35 and 36 which are parts of a fulcrumed elevating frame, made up of said arms 35 and 36, a tubular cross member 37 welded thereto, a pair of bell crank arms 38 and 39, a tubular cross member 40 welded thereto and diagonal braces 41 and 42. The entire elevating frame is fulcrumed upon pivots 43 and 44, so that the lower end of the arms 35 and 36 which engage the treating unit 2 are capable of a swinging movement, a large component of which is vertical. To produce this movement a pair of hydraulic cylinders 45 and 46 are interposed respectively between rearward extensions 47 and 48 secured to the rear of the transporting unit and the cross member 40. When fluid is fed to the cylinders 45 and 46, the elevating frame is raised, and when fluid is exhausted, it is lowered.

A supply of fluid for cylinders 45 and 46 is provided by continuously running pump 49 mounted on engine 10 to be driven thereby. Connections between the pump 49 and the cylinders 45 and 46 are of conventional form and therefore not shown except diagrammatically in Fig. 6. In Fig. 6, pump 49 is shown arranged to discharge fluid into pipe 50 which joins with volume limiting valve 51 through which fluid has free passage into pipe 52. Valve 51 is so arranged that a branching stream of fluid of limited volume may escape therefrom into pipe 53 for purposes to be later described. Fluid passing through pipe 52 is free when called for to branch therefrom through pipe 54 and thence by passing through pipe 55 to reach piston type reversing valve 56 having operating handle 57. The valve 56 is provided with three ports all of which are closed with the operating handle 57 in off position. With the handle 57 in lifting position the pipe 55 is brought into communication with the pipe 58 and the other port is closed and fluid is thus supplied through branch pipes 59 and 60 to the cylinders 45 and 46. With the handle 57 in lowering position, the port connecting with pipe 55 is closed and pipe 58 is brought into communication with discharge pipe 61 and thence through return pipe 62 with a sump 63 to which fluid may freely drain.

Pipe 52 from which pipe 54 branches joins with a second volume limiting valve 64 similar in all respects to the valve 51 through which fluid may freely pass to pipe 65 while a limited side stream may escape into pipe 66 for a purpose to be more fully described. Pipe 65 in turn joins with a fixed aperture back pressure orifice 67, so constructed as to permit fluid to pass therethrough but to maintain ahead of it a pressure equal to the intended operating pressure of the system. The capacity of pump 49, at the pressure maintained by orifice 67 is such that it exceeds the volumetric requirement of the cylinders 45 and 46 when lifting at the maximum rate desired, by an amount in excess of the maximum rate of es-

cape of fluid through pipes 53 and 66, previously referred to, and pipe 68 not yet described. All excess fluid passes through orifice 67, pipe 69, and pipe 62 to sump 63. Operating handle 57 is located as shown in Fig. 3 within easy reach of the operator.

For additionally adjusting the position of the treating unit 2 with respect to the transporting unit 1 and the soil to be worked upon, a pair of turnbuckle rods 70 and 71 which support the overhanging rear portion of the treating unit 2 are joined at their upper ends respectively with bell cranks 72 and 73 pivotally mounted respectively upon the arms 38 and 39. The cranks 72 and 73 are subject to positional adjustment by and are in engagement respectively with the plungers of a pair of hydraulic cylinders 74 and 75 supported at their lower ends respectively upon arms 35 and 36. In this way there is provided a limited amount of tilting movement of the unit 2 with respect to the arms 35 and 36 to which it is pivotally connected by the pins 76 and 77.

Supply of fluid and control of the same for actuating cylinders 74 and 75 is similar to that described in connection with cylinders 45 and 46. Fluid is supplied through pipe 68 and reversing valve 78 which connects through pipe 79 with pipes 80 and 81 as shown in Fig. 6 only. Exhausted fluid from the cylinders 74 and 75 and the valve 78 passes through pipe 82 into pipe 62 and thence into sump 63. For controlling valve 78 an operating handle 83 located as shown in Fig. 3 is provided.

By means of the mounting arrangement shown and described, the treating unit 2 may be brought to and held at any working level desired by manipulation of the cylinders 45, 46, 74, and 75, or may be lifted clear of the surface upon which the apparatus is traveling, so that the apparatus may travel to and from the place where work is to be carried on. In the holding position the valves 56 and 78 are in their lapped positions. Furthermore, by manipulation of cylinders 74 and 75, the angular relationship of the treating unit 2 with respect to the base of treads 3 may be readily adjusted. For example, if the work being performed passes over the crest of a hill, the operator can permit sufficient fluid to escape from cylinders 74 and 75 so that the rear of the treating unit 2 drops just the right amount to conform to the change in configuration of the grade. If the grade is changing in the opposite way, the rear of treating unit 2 can be raised accordingly. Thus the operator can, without interruption of the work, continuously treat a substantially uniform layer of the material being worked upon regardless of alteration in the grade.

The overhanging treating unit 2 is without any trailing support in the form of wheels or skids which would bear upon the completed treated layer. This is of importance because the treated layer after formation must be compacted by rolling and any area precompacted prior to rolling persists as a non-uniform area in the finished pavement after rolling. The avoidance of trailing support for the overhanging treating unit 2 is accomplished according to this invention by placing the heavy prime mover 10 far forward on the transporting unit 1, thus bringing the combined center of gravity of the entire assembly well within the ends of the treads 3. It is preferred that the disposition of loading be such that this combined center of gravity under static

conditions is located somewhat to the rear of center of treads 3 so that the effect of the engagement of unit 2 with the soil being worked upon will bring the resultant loading of the treads 3 close to the center thereof under dynamic or working conditions.

Housing.—The treating unit 2 is mounted within a housing serving as a frame made up of double walled side plates 84 and 85 joined at the front by curved end plate 86 and at the rear by curved end plate 87. The open top of the rectangular frame thus provided is covered by four similar removable hatch covers each designated by the numeral 88. To ensure rigidity, a tubular cross brace 89 is secured to and extends between the side plates 84 and 85 directly beneath the points of attachment of the rods 70 and 71. This frame is pivotally secured to the arms 35 and 36 as previously described by means of the pins 76 and 77 which are held respectively between the double walls of side plates 84 and 85.

Cutting rotor.—Mounted to turn in bearings provided therefor in the side plates 85 and 84 near the front thereof is a cutting rotor 101 carried on a shaft 90 having a tubular center portion with reduced extensions at the ends. One of these extensions is designated 91 and appears in Fig. 5 where it may be seen as extending through a bearing 92 and outwardly beyond the side plate 84.

Secured by welding to the tubular portion of shaft 90 in axially and angularly spaced arrangement as shown, are a plurality of cutting tine sprockets 93. The inner end of a flat spring-steel tine 96 is removably clamped in each of the sockets 93. The cutting ends of the tines 96 are enlarged, and if desired, armed with material of exceptional abrasion resistance. The angular spacing of the sockets 93 and the tines held therein is so distributed that successive tines engage the material being excavated in rapid succession, so that there is an avoidance of the shock which could otherwise be occasioned by a large number of tines all initiating their cutting action at the same moment. The cutting rotor is operated in a clockwise direction as viewed in Fig. 1 and preferably at such a rate with relation to the forward speed of the apparatus that material excavated is cut or shaved away in small increments akin to the action of a milling cutter. The rate of rotation of the cutting rotor furthermore is preferably such that material is projected against the target rotor with considerable force to cause a disintegrating and pulverizing action.

Target rotor.—Spaced from and parallelly disposed to the rear of cutting rotor 101 is a target or material intercepting rotor 102 mounted on a shaft 103 having a tubular center portion with reduced end extensions carried in bearings held in the side plates 84 and 85. One of the extensions of shaft 103 is designated 105 and appears in Fig. 5 where it may be seen passing through a bearing 104 held in the side plate 84. The tubular portion of shaft 103 is provided throughout its length with four equally spaced radially extending longitudinal fins 106 welded in place.

Attached to the fins 106 by bolting are a plurality of closely spaced resilient steel tongues 107 of uniform length, the tips of which are bent slightly as shown and cut at a slight angle so as to sweep a substantially cylindrical surface in spite of the bend of the tip. The tips of the tongues 107 are bent so as to cause material engaged by the same to move laterally to some ex-

tent. As appears more clearly in Fig. 5, some of the tongues 107 are bent to cause lateral movement of material in one direction and some in the other direction. The arrangement is such that one pair of diametrically opposed sets of tongues tends to divide material at the center of rotor 102 and move it toward the ends thereof; while the intervening pair of diametrically disposed sets of tongues tends to gather material from the ends of rotor 102 and move it toward the center. This general arrangement is subject to the exception that in the case of the sets of tongues bent to cause outward movement of material, the outer tongues designated 107A are oppositely bent to minimize loss of material beyond the ends of the rotor 102. Since the object sought is an alternate transverse mingling action of the material, other arrangements of the bent tongues 107 may be resorted to with equal effectiveness, and some modification in this regard may be found advantageous in handling different types of material.

The rotor 102 is arranged to be turned in a counterclockwise direction by driving means to be described more fully hereinafter. The rate of rotation of target rotor 102 is preferably such that material deposited before it and impinging upon it by reason of the action of cutting rotor 101, is moderately tossed back into the more rapidly turning cutting rotor 101 from which it is again returned forcibly into the target rotor 102. In the course of the back and forth movement of the material thus created, it is raised to successively higher levels in the target rotor 102 until it is finally caught by the target rotor 102 and tossed rearwardly. In this way the material is subjected to repeated impact and thus pulverized to a very substantial degree. Furthermore, in cases where dry material, such as sand or Portland cement, is spread upon the surface being worked upon in advance of the apparatus while working, a very thorough mixing and intermingling of the added dry particles with the pulverized soil is accomplished. In aid of this intermingling and mixing action, the slight lateral movement caused by the bent tips of the tongues 107 brings about a lateral blending also, which tends to obliterate any lack of uniformity transversely of the work strip caused by streaked spreading of the dry material.

While the target rotor 102 is in effect a complete paddle wheel because of the close spacing of the tongues 107, each tongue is independent and resilient so that it may yield if an obstruction such as a deeply buried boulder not cut away by the resilient cutting tines of the cutting rotor 101 is encountered. Because the tongues 107 are spaced from one another slightly, and are bent at their tips and may yield and thus incompletely sweep the excavated subgrade, successive sets of tongues making up the rotor 102 are staggered slightly as may be observed in Fig. 5 to ensure engagement of all material excavated by the target rotor 102.

Blading mill.—Behind the target rotor 102 within the frame of the treating unit 2, and mounted upon tubular shafts 108 and 109, extending between bearings secured in side plates 84 and 85, are a pair of blading mill rotors 110. The rotors of mill 110 are furnished with a plurality of welded in place blade sockets 111 spaced from one another as shown. Carried in the blade sockets 111 are the shank portions of replaceable blades 112.

The shaft spacing of the blading mill rotors

110 is less than the diameter of one of the rotors and thus the blades thereof overlap. For this reason, the blading mill rotors 110 are arranged to be driven in synchronism.

Material tossed rearwardly by the target rotor 102 when operating at preferred speed is delivered into the forward blading mill rotor 110 at a level centering about a plane slightly above the rotor shaft 108 from which level it is carried downwardly in front of the forward rotor shaft 108 and thence to the rear and upwardly between the two blading mill rotors where it undergoes a shearing, squeezing, and tumbling action to accomplish a thorough coating of the particles of the material with the added bonding agent. Much of this material is then thrown forwardly again over the forward blading mill rotor for return with fresh material and for a repetition of the treatment which occurs between the two blading mill rotors. The remainder of the material not carried forwardly for recycling is carried over the top of the rear blading mill rotor and deposited on the subgrade in condition for rolling to complete the pavement.

Treating unit drive system.—Power to cause the described movements of the several rotors contained in the treating unit 2 is supplied by the main engine 10 through a drive system commencing with the chain 15 running on the sprocket 13. Referring to Fig. 4, it will be seen that the chain 15 meshes with a sprocket 118 on a power input shaft 119 of a clutch contained within a housing 120. As appears in Fig. 3 the clutch within the housing 120 is controlled by a clutch throwout lever 122 mounted within reach of the operator and connected with the clutch by clutch throwout rod 121. Extending rearwardly from the housing 120 is a clutch output shaft 123 drivingly connected at its rear end with the pinion of a bevel gear speed reducer 124. The housing of speed reducer 124 serves also as a support for the previously described pivot 43 upon which arm 35 is mounted. An output shaft 125 for the speed reducer 124 is concentric with and passes outwardly through the pivot 43 and carried at its outer end a double sprocket wheel 126.

The communication of power from the transporting unit 1 to the treating unit 2 is by means of a double chain 127 which is in mesh with the sprocket 126 at its upper end and in mesh at its lower end with a double sprocket 128 carried on and secured to the shaft extension 91 of the shaft 90.

Also secured to the shaft 91 is a double sprocket 129 for communicating power to the rotors to the rear in the treating unit 2. The target rotor shaft has mounted on it a gear 131 within the side plates 84 meshing with a gear 132 on a stub shaft 133 which extends outwardly from the outer plate 84 and has secured to it a double sprocket 135 in mesh with and driven by a double chain 134 which is in driven engagement with double sprocket 129. In this way the target rotor is driven at a rate substantially lower than that of the cutting rotor 101.

Also carried upon the shaft 133 and secured thereto is a double sprocket 136 which is provided to transmit power for operation of the blading mill rotor 110. Secured in the side plate 84 in the position of and extending from one blading mill rotor to the other is a synchronizing gear housing 137 which provides bearing support for the shafts 108 and 109. Shaft 108 extends outwardly from the housing 137 and has secured to it a double sprocket 138 which is in mesh with a

double chain 139 in driven engagement with sprocket 136. Also secured to the shaft 108 but within the housing 137 is a pinion 140 which is in mesh with an idler pinion 142, in turn in mesh with an idler pinion 143 which in turn drivingly engages a pinion 144 secured to shaft 109. In this way the two blading mill rotors are driven and maintained positively in synchronism without danger of jumping of sprocket teeth by a chain, thus avoiding a condition in which the blades will clash with one another. The synchronizing gear connection between the rotors 110 causes these rotors to rotate toward each other.

Fluid supply.—Where soil cement is being prepared by the apparatus of this invention through the use of Portland cement, or where a bituminously bonded pavement is being constructed, the necessary water or fluid bitumen is sprayed against the material undergoing treatment within the treating unit 2. For this purpose the tanks formed by frame members 4 and 5 of the transporting unit 1 are employed. These tanks hold a limited quantity of fluid as compared with the amount dealt with per hour by the apparatus and serve only as a reserve supply to permit avoidance of interruption while an exhausted conveying tank truck is being replaced by a full one. However, fluid supplied by the conveying tank truck is first introduced into one of the tanks 4 or 5, and in the case of water is put under pressure through a pump 150 driven by an auxiliary engine 145, and in the case of fluid bituminous a plunger type pump 148 is driven through a belt 147 from the engine 145.

In either case these fluids are carried under pressure from the pump through pipes 161 and 179 to proportioning valves 162 and 171 and thence through pipes 164 and 173 which connect respectively with pipes 167 and 176. The pipe 167 connects with a distributor pipe 169 through a shut off valve 168. The pipe 176 connects with a distributor pipe 178 through a shut off valve 177. Both distributor pipes 169 and 178 may be connected together through a valve 202. The valve 168 is operated hydraulically by a hydraulic cylinder 190 connected by pipes 193 and 192 to a pressure pipe 53 and to a release pipe 195 controlled by a manually operated valve 196 whose outlet discharges into the pipe 62 that leads to the sump 63 heretofore described. The valve 177 is operated by a hydraulic cylinder 191 connected by pipes 200 and 199 to a pressure pipe 66 and a pressure release pipe 198 connected to a manually operated valve 197 whose outlet also connects with the pipe 62 leading to the sump. In all positions, but the full open positions of the valves 196 and 197, the resultant pressure from the pipes 53 or 66 to the pipes 192 or 199 will cause the hydraulic cylinder 190 or 191 to open the valves 168 and 177. Between the pipes 161 and 164 is the proportioning valve 162 whose discharge leads back to the supply tanks through a pipe 163. The valve 162 is operated by a hydraulic cylinder 184 which is connected by a pipe 194 to the pipe 192. As noted before, the pipe 192 connects both with the pressure supply pipe 53 and the relief pipe 195, so that as the valve 196 is opened and more of the pressure fluid can discharge to the sump, less pressure will be exerted through the hydraulic cylinder 184 on the valve 162, so that this valve will be moved to a closed position. The details of this are not shown in this application as they are separate subject matter. The proportioning valve 171 connects with the pipes 170 and 173 and has a return pipe 172 leading to the supply tanks. This valve is

operated by a hydraulic cylinder, which is designated 184, similar to that for the valve 162, and connects the pipe 201 with the pipe 199, which as previously noted connects with a pressure pipe 66 and a release pipe 188. The action of this hydraulic cylinder through the opening of the valve 197 is similar to that just described in connection with the valve 162, and since this hydraulic mechanism for shutting off and controlling the amount of binder fluid does not form a part of the present invention, further description thereof is deemed unnecessary.

From the above description it will be noted that while the machine is operating, power is transmitted to the cutting rotor 101, the intercepting rotor 102, and the blading mill rotors 110. The action of these rotors on the material is more particularly described in the previously referred to application, but in general the action is to blend and pulverize the material being treated, mix this blended and pulverized material with a binder ingredient introduced through the pipe 169, and then mix the binder ingredient with the material in the blading mill before depositing the same on the subgrade.

In starting a typical treating operation, the treating unit 2 is raised by the action of both sets of lifting cylinders, and then cylinders 45 and 46 are gradually relieved of their fluid while the rotors of the treating unit are turning. As soon as established grade is reached, fluid is allowed to escape gradually from cylinders 74 and 75 while the transporting unit 1 is placed in forward movement. Escape of all fluid from cylinders 75 and 74, however, is delayed until the amount of forward movement of transporting unit 1 is substantially equal to the effective length of the treating unit 2 at which time all rotors may be brought to the operating grade. In this way the apparatus of this invention may be conveniently operated by a single operator so as to "dig itself in" after which the routine treatment of the strip to be worked upon likewise progresses under the complete control of a single operator as long as supplies equal to the requirements of the machine are furnished.

While this invention has herein been described by reference to one specific instance of its embodiment and use, it is intended that the protection to be afforded hereby be not unnecessarily limited thereby, the intent being that such protection shall extend to the full limit of the inventive advance herein disclosed as defined by the claims to be hereto appended.

What I claim as my invention is:

1. In a soil treating apparatus, the combination comprising a transporting unit movable over a surface to be treated and including a frame, an overhanging soil treating unit disposed to the rear of said transporting unit, an elevating member having a pair of arms pivoted at the rear of said frame on a single horizontal axis for vertical swinging movement and pivotally connected at their ends to the front of said soil treating unit, power operated means connected to said arms to swing said elevating member and to hold the same in adjusted positions to which it is swung whereby the front end of said treating unit may be raised and lowered, and a supplementary power operated lifting means mounted on and carried by said elevating member to move therewith cooperatively engaging said treating unit at a point spaced from the pivotal attachment of said elevating member the same being adapted to support the rearward end of said treating unit and to

adjustably lift and lower the same independently of the movement of said elevating member whereby said treating unit may be leveled and inclined thereby in each adjusted position of said elevating member, and means on said transporting unit for controlling said power operated means and said supplementary power operated lifting means.

2. In a soil treating apparatus, the combination comprising a transporting unit movable over a surface to be treated and including a frame, an overhanging soil treating unit disposed to the rear of said transporting unit, an elevating member having a pair of arms pivoted at the rear of said frame on a single horizontal axis for vertical swinging movement and pivotally connected at their ends to the front of said soil treating unit, hydraulic means connected to said arms to swing said elevating member and to hold the same in adjusted positions to which it is swung whereby the front end of said treating unit may be raised and lowered, and a supplementary hydraulic lifting means mounted on and carried by said elevating member to move therewith cooperatively engaging said treating unit at a point spaced from the pivotal attachment of said elevating member the same being adapted to support the rearward end of said treating unit and to adjustably lift and lower the same independently of the movement of said elevating member whereby said treating unit may be leveled and inclined thereby in each adjusted position of said elevating member, and control means for said first named hydraulic means and said supplementary lifting means mounted on said transporting unit in a position accessible to the operator thereof.

3. In a soil treating apparatus, the combination comprising a transporting unit movable over a surface to be treated, an overhanging soil treating unit disposed to the rear of said transporting unit, a pair of elevating arms mounted for vertical swinging movement on the rear of said transporting unit on a single horizontally disposed pivotal mounting and pivotally attached at their swingable ends to the front of said soil treating unit, means for swinging said elevating arms and for holding the same in adjusted positions to which they are swung whereby the front end of said treating unit may be raised and lowered, and a supplementary lifting means mounted on and carried by said elevating arms to move therewith and cooperatively engaging said treating unit at a point spaced from the pivotal attachment of said elevating arms the same being adapted to support the rearward end of said treating unit and to adjustably lift and lower the same independently of the movement of said elevating member whereby said treating unit may be leveled and inclined thereby in each adjusted position of said elevating arms and control means on said supporting unit for said supplementary lifting means.

4. In a soil treating apparatus, the combination comprising a transporting unit movable over a surface to be treated, an overhanging soil treating unit disposed to the rear of said transporting unit, a pair of elevating arms mounted for vertical swinging movement on the rear of said transporting unit on a single horizontally disposed pivotal mounting and pivotally attached at their swingable ends to the front of said soil treating unit, a pair of hydraulic cylinders interposed between said transporting unit and said arms for swinging said arms and for holding the same in adjusted positions to which they are swung whereby the front end of said treating unit may

13

be raised and lowered, a second pair of hydraulic cylinders mounted on and carried by said elevating arms to move therewith and cooperatively engaging means joined to said arms and to said treating unit at points spaced from the pivotal attachment of said elevating arms and controlled by said second pair of cylinders the same being adapted to support the rearward end of said treating unit and to adjustably lift and lower the same independently of the movement of said elevating arms whereby said treating unit may be leveled and inclined thereby in each adjusted position of said arms, and control means on said transporting unit for said hydraulic cylinders.

5. In a soil treating apparatus, the combination comprising a transporting unit movable over a surface to be treated including a frame, an overhanging soil treating unit disposed to the rear of said transporting unit, a pair of rigidly interconnected elevating arms mounted on said frame for vertical swinging movement about a single point of pivotal oscillation on the rear of said transporting unit and pivotally connected at their ends to the front of said soil treating unit, a pair of hydraulic cylinders interposed between said arms and said transporting unit for swinging said arms and for holding the same in adjusted positions to which they are swung whereby the front end of said treating unit may be raised and lowered, a bell crank lever mounted on each of said arms, and a supplementary hydraulic cylinder mounted on and carried by each of said arms to move therewith interposed between the same and said bell crank levers, and supporting rods operatively connecting said bell crank levers to said treating unit at points spaced from the pivotal attachment of said arms the same being adapted to support the rearward end of said treating unit and under the action of said supplementary hydraulic cylinders to adjustably lift and lower said rearward end independently of the movement of said arms whereby said treating

14

unit may be leveled and inclined thereby in each adjusted position of said arms, and control means on said transporting unit for all of said hydraulic cylinders.

5. The combination with a transporting unit, of an overhanging soil treating unit disposed to the rear of said transporting unit, a pair of rigidly interconnected bell cranks having a horizontally disposed pivotal mounting on said transporting unit and having arms pivotally connected by a horizontally disposed pivotal mounting to the forward end of said treating unit, means for swinging said bell cranks to raise and lower the forward end of said treating unit, a pair of bell crank levers carried by the other arms of said bell cranks operating connections between said second named bell cranks and the rearward portion of said treating unit, and means for swinging said second named bell cranks for raising and lowering through said operating connection the rearward portion of said treating unit to vary its inclination about its forward pivotal mounting.

HENRY C. HETTELSATER.
